UNITED STATES PATENT OFFICE.

CLEMENT V. HILL, OF TRENTON, NEW JERSEY.

FASTENER FOR DOORS.

Application filed December 22, 1925. Serial No. 77,037.

My present invention is an improvement in the construction of fasteners for doors shown in my Patent No. 1,123,741 dated January 5, 1915.

For the purpose of illustrating my invention I have shown it mounted on a refrigerator door.

The object of my invention is to provide a fastening mechanism which will hold the door tightly on its jamb with an air tight joint, said mechanism being so constructed that it may be as readily operated from the inside of the door as from the outside thereof, the latch bolt being of a type that will automatically engage its keeper as soon as the door is closed, there being tension means to hold the bolt firmly in its locked position, but the mechanism for operating the bolt is such that the tension of the said means to overcome, with a minimum pull in the act of opening the door; and with these and other objects in view my invention consists of the parts and combination of parts, as will be more fully hereinafter set forth.

In the drawings:

Figure 1 is a front elevation of a portion of a door and its jamb with my improved fastener applied thereto.

Figure 2 is a vertical section on the line 30 2-2, Figure 1.

Figure 3 is a large detail end view of a door with my invention applied, some of the parts being shown in section.

Figure 4 is an enlarged detail rear elevation of the front plate.

Figure 5 is an enlarged perspective detail view sealing plate and operating rod, parts being broken away.

The reference numeral 1 designates a jamb, and 2 a door of suitable construction.

The keeper 3 is secured to the jamb by means of the screws or bolts 4, and is provided with a nose 5 having a cam face 6 and a cam face 7, the latter cam face, when the keeper is assembled on a door jamb, being spaced from the jamb to form a recess 8 for the reception and retention of the latch-bolt.

A plate face 10 is secured to the door by any suitable means, such as screws, and is substantially of L shape to provide a base upon which the working parts of the latch may be mounted thereby eliminating the liability of the parts being lost in transit and reducing to a minimum the number of

screws or bolts necessary to secure the parts to a door.

Arms 11 and 12 are formed integral with the base plate 10 and project forwardly therefrom when the plate is secured to a door. A revoluble shaft 13 is journaled in said arms 11 and 12 and is provided with a crank arm 14 on the end of which is mounted an antifriction roller 15 which is adapted to enter the recess 8 in the keeper and thereby securely latch the door in its closed position, as shown in the drawing.

An arm 16 is keyed to the shaft 13 by means of which the shaft is revolved and the latch bolt withdrawn from the keeper when the parts are operated in the act of opening and closing the door. This arm is provided with a yoked end 17 to which is pivotally secured a link 18, the end thereof being adapted to receive the forked end 22.

The door is provided with a transverse opening 19, in which the rod or stem 20 is positioned, the opening being, relatively, of greater diameter than the rod or stem shown, the inner end of the rod or stem being provided with a knob 23. The inner end of the opening is closed by means of a cup plate 24 having an opening through which the rod passes, said plate being packed with a packing 25, preferably felt, which will prevent the ingress and egress of air around through the opening 19, which, in the case of refrigerators, is very essential.

The forward or outer end of the rod is provided with an integral operating handle 26 and with a striking plate or lug 27 which is of such size that it will close and seal the outer end of the opening 19, when the door is closed, thus providing another seal against the ingress or egress of air. I secure to the operating rod 20 under the lug 27 a resilient packing 28 which functions to reduce the noise of impact and also as a sealing element. Intermediate the striking plate 27 and handle 26 the rod 20 is enlarged as at 29 through which is formed a slot 30 in which is pivotally secured the reduced upper end 31 of the link 18, and the reduced lower end 32 of the upper link 33, the upper end of the link 33 being forked is pivoted to the lug 34 which is integral with the face plate 35.

The face plate 10 is, preferably, provided with a flange 35 whereby the plate when se-

cured to the door is spaced therefrom as will be more clearly seen in Figure 3. On the rear face of the plate 10, in proximity to the openings 36, I provide a slideway 38 on which is slidably mounted the sealing plate 39 which is provided with an opening through which the operating rod 20 passes. It will be noted that the sealing plate 39 is of greater area than the hole 36 in the face plate, whereby the hole 36 is always covered by said plate 39, irrespective of any movement of the operating rod.

The operating rod 20 is provided with screw threads on which is mounted a tension nut 40 which abuts the short tube 41 loosely mounted on the rod 20. A coiled spring 42 is secured around the rod 20, one end of which is seated against the sealing plate 39, while its other end is seated on the short tube 41, whereby the spring not only puts the operating rod under tension but it also firmly holds the sealing plate 39 in the slideway 38 and effectively holds the plate 39 across the opening 36 of the face plate to prevent air from passing through the opening 36.

A sleeve 43 loosely surrounds the spring 42, tube 41, tension nut 40 and a portion of the operating rod 20 and its forward end 30 bears against the sealing plate 38 which effectively seals that end of the sleeve as best seen in Figure 3. The rear end of the sleeve 43 is provided with a shoulder 44 on its rear end which is adapted to bear on the rear plate 45 the sleeve being reduced in exterior diameter forming a rearwardly projecting lip 46 which passes through an opening in the rear plate 45.

When the door is closed the parts are in the position shown in Figure 2. Now assuming that it is desired to open the door the parts are operated, from the outside, by grasping handle 26 and pulling it in the natural direction to swing the door open, when the parts will assume the position shown in Figure 3 and by continued pull the door will swing to full open position. When the handle 30 is pulled outward the outer end portion of the rod 26 is elevated, as shown in dotted lines in Figure 3, by reason of the fact that the upper end of the link 33 is anchored to the base plate 10 and swings in an arc from that point, and this upward movement results in pulling the link 18 bodily upward thereby, elevating the inner end of the arm 16 and thus revolving the shaft 13 against the tension of the spring 42, thus swinging the arm 14 and elevating the roller 15 above the nose 5 whereupon the door is free to be swung open. Notwithstanding this vertical movement of the rod 20, the opening 36 in the front plate is always closed against the passage of air by the sliding sealing plate 39.

In closing the door the roller 15 rides up

the cam face 6 and drops into the recess 8 and by the cooperation of the spring 42 and the cam face 7 the door is pulled against the jamb and forms therewith a tight joint.

In the use of refrigerators it is customary to close the door tightly so that it is necessary to provide some means for operating the latch from within the refrigerator therefore I extend the rod or stem 20 within the refrigerator and provide it with a knob 23 so that the lock may be operated by pushing the rod outward. I prefer to use a knob on the inner end of the rod as it presents an enlarged surface against which the body may be conveniently pressed, in case the operator requires both hands to carry goods from the refrigerator.

It will be observed that in operating this fastener no unusual or unnatural movements are necessary; the natural movement of the arm in opening and closing the door being all that is necessary to operate the fastener.

By reason of the link movement herein described which gives a very powerful leverage, I am enabled to put the spring 42 under very heavy tension which results in a stronger pull of the latching roller 16 on the cam face 7, which in turn results in a tighter joint between the door and jamb.

What I claim is:

1. In a fastener for doors, the combination with a latch, and a face plate having an opening therethrough, of an operating rod adapted to pass through the opening in said plate and of materially less diameter than said opening, a sealing plate loosely mounted on said rod and adapted to close the opening in the face plate around said rod, a coiled spring around said rod, one end of which is seated on said sealing plate, and a tension nut on said rod against which the other end of the spring is seated.

2. In a fastener for doors, the combination with a latch, and a face plate having an opening therethrough, of an operating rod adapted to pass through the opening in said plate and of materially less diameter than said opening, a sealing plate loosely mounted on said rod and adapted to close the opening in the face plate around said rod, a coiled spring around said rod, one end of which is seated on said sealing plate, and a tension nut on said rod against which the other end of the spring is seated, a sleeve surrounding said spring and a portion of the operating rod, and a handle on each end of the operating rod.

3. A lock of the character described including a face plate having an opening therethrough to receive the operating rod of the lock, a slideway on the rear face of said plate extending above and below said opening, and a sealing plate mounted on said slideway and having an opening there-

through of less diameter than the opening in the face plate, and adapted to receive the operating rod therethrough with a snug fit.

4. In a fastener for doors, the combination 5 with a latch for holding the door closed, an operating rod adapted to extend through an opening in a door and having a limited vertical movement at its outer end, a sealing plate mounted on and movable vertically 10 with said rod and covering the opening through the door in all positions of the rod, and a spring around said rod, one end of which is seated on said plate.

5. In a fastener for doors, the combination 15 with a latch for holding the door closed and mounted upon an axis parallel to the vertical plane of the door, of an operating rod extending through a transverse opening in the door, said opening being of greater diameter than the rod, a handle on each end 20 of the rod, a link pivotally connected to the door and to the outer end of the rod, a link pivotally connected to the said rod and to said latch, whereby a movement of the rod in the direction of its axis will rotate said latch upon its axis, a sealing plate of greater 25 area than the opening in the door and mounted on and having a snug fit with said operating rod, whereby the opening in the door is sealed irrespective of the position of the 30 said rod.

6. In a fastener for doors, the combination 35 with a face plate having an opening therethrough, a slideway on the rear face of the plate and a sealing plate slidably mounted

in said slideway, an operating rod slidably mounted in an opening in said sealing plate, a coiled spring mounted on said rod, one end of which is seated on said sealing plate, a tension device screw threaded on the said rod against which the other end of the spring is seated, a sleeve surrounding the spring, tension device and a portion of the rod, and bearing at its forward end on and sealed by the sealing plate, an operating handle at 40 each end of the rod, and a packing on the rod adapted to seal the opening in the face plate when the fastener is in closed position.

7. In a fastener for doors, the combination 45 with a face plate having an opening therethrough, a slideway on the rear face of the plate and a sealing plate slidably mounted in said slideway, an operating rod slidably mounted in an opening in said sealing plate, a coiled spring mounted on said rod, one 50 end of which is seated on said sealing plate, a tension device screw threaded on the said rod against which the other end of the spring is seated, a sleeve surrounding the spring, tension device and a portion of the rod and bearing at its forward end on and sealed by the sealing plate, an operating handle at 55 each end of the rod, and a packing on the rod adapted to seal the opening in the face plate when the fastener is in closed position, and a bearing plate for the rear end 60 of the said sleeve.

In testimony whereof I affix my signature.

CLEMENT V. HILL.
